[57] CLAIM

The ornamental design for a coating thickness gauge, as
shown and described.

DESCRIPTION

FIG. 1 is a perspective view of a coating thickness
gauge showing my new design;

FIG. 2 is a top plan view;

FIG. 3 is a front elevational view;

FIG. 4 is a right side elevational view;

FIG. 5 is a left side elevational view;

FIG. 6 is a rear elevational view;

FIG. 7 is a bottom plan view;

FIG. 8 is a front elevational view, shown in an alternate
condition of use; and,

FIG. 9 is a front elevational view of a second embodiment
showing my new design thereof.

FIG. 1

FIG. 2

FIG. 3

FIG. 4

FIG. 5

FIG. 6
